APPARATUS FOR CENTERING SHANKS IN CASTING DIAMOND BITS

Mano L. Tucker, Detroit, Mich., assignor to Chicago Pneumatic Tool Company, New York, N. Y., a corporation of New Jersey

Application November 9, 1944, Serial No. 562,727

3 Claims. (Cl. 22—58)

1

This invention relates to apparatus for casting composite diamond bits.

The main object of the invention is to provide apparatus containing a die in which the diamonds are properly supported for casting metal or alloy to encompass them and having means for accurately centering a bit blank over the diamonds so that the resulting cast bit will run true during drilling.

A further object is to provide such a simple apparatus for casting diamond cutting and drilling bits that only very few parts are required to be assembled to form the mold for casting, and, after casting, to be taken apart to release the cast bit.

Other objects and the advantages of the invention are set forth more fully in detail in the following specification in conjunction with the accompanying drawing, in which:

Fig. 1 is a vertical section of the entire apparatus with a complete cast diamond bit in place;

Fig. 2 is a vertical section of the cast bit after release from the mold and before trimming;

Fig. 3 is a similar view of the cast bit after the excess cast metal has been trimmed off;

Fig. 4 is a vertical section of the bit blank alone before applying cast metal or attaching diamonds thereto;

Fig. 5 is another view of the same bit blank as seen from the bottom in Fig. 4;

Fig. 6 is a plan view of the main die of the apparatus; and

Fig. 7 is a transverse section of the same die taken along the line 7—7 in Fig. 6.

Heretofore the practice of setting and casting diamonds in a group to form a diamond bit has frequently entailed the use of more or less complicated apparatus requiring a large outlay not only for the equipment but also for skilled labor to cast the bits. In some cases the bits were made by makeshift methods and means in connection with which the molten metal was first cast and then mounted separately on the bit blank with the result that all too often the metal holding the diamonds and the bit blank did not run concentrically.

In order to overcome these and other disadvantages and particularly with the foregoing objects in view, it is now contemplated to hold the bit blank in true concentricity with a portion in a die serving to support the diamonds and receive the molten metal as will now be set forth in detail.

Hence, referring again to the accompanying drawing the bit blank 10 (Fig. 4) is mounted on

2

a centering plug or stud 11 and a holding cap 12 is passed down upon the plug and screwed upon thread 13 of the bit blank until the upper end of the latter engages against a radially extending locating flange or projection 14 and also shoulder 15 of the cap engages against the same flange from above. At the same time the lower end 16 of the holding cap rests against shoulder 17 on the bit blank, the latter and the holding cap as well as the centering plug are thus held in rigidly assembled relation.

The die or holder 18 is placed in position upon the vacuum chamber 19 so as to rest in the recess 21 in the upper part of said chamber. The mentioned die has an annular groove 22 (Figs. 6 and 7) open to the top with a generally concave bottom 23 perforated by a plurality of holes 24 extending down to the lower surface 25 of said die and at their upper extremities being adapted to seat the cutting diamonds 26. The vacuum chamber 19 is connected to an exhaust pump (not shown) by pipe 27 and the pump started so that a partial vacuum is created in chamber 19. The diamonds are individually seated in the upper ends of holes 24 so that the entire bottom 23 of the annular groove is substantially studded with them, being held in place by the downward suction through the holes 24 past said diamonds.

The bit blank assembly previously described is set upright on die 18 by fitting a central tip or pilot portion 28 of the centering plug 11 into a central aperture 29 in the die 25 which is concentric with the annular groove 22 so that the plug stands upright with its shoulder 31 resting on the die upon the annular area 32 around said central aperture, thus ensuring the concentricity of the bit blank with the groove. The flask ring 33 is also placed in position with its lower recess portion 34 fitted upon the top 35 of the die and the molten metal or alloy 36 poured into the upper concave portion 37, and flowing down over and encompassing the diamonds 26 and also passing through anchoring holes 38 in the lower reduced portion 39 of the bit blank. The suction prevents the diamonds 26 from rising under the buoyant force of the metal which has a greater specific gravity. As soon as sufficient casting metal has been poured, the exhaust pump is stopped and the molten mass is permitted to cool. As it does, the molten metal shrinks to a very tight fit upon reduced portion 39 of the bit blank and in the holes 38, thereby adhering so firmly to the bit that it is virtually integral therewith. As soon as the die arrangement is to be disas-

sembled the following procedure may be carried out.

When the casting is sufficiently cool the die 18 and the ring 33 as well as the casting and the bit blank assembly are removed from the vacuum chamber and the die cautiously removed from the casting and the flask ring, after which the latter is removed. Then the holding cap 12 is unscrewed from threads 13 on the bit and removed from the centering plug 11, and thereafter the latter is withdrawn from within the bit, with said bit appearing substantially as shown in Fig. 2. The cast metal 41, 42 is trimmed off preferably by turning in a lathe to produce a finished bit as shown in Fig. 3, wherein it is evident that the major portion of the cast metal 36 above the portion thereof actually holding the diamonds has been cut substantially to the inside and outside diameters 43 and 44 of the bit blank to provide drilling clearance for the bit.

An example of an alloy suitable for use as the casting metal 36 consists of 2 percent beryllium, 0.35 percent nickel and the remainder copper.

In drilling the holes 38 it is often found desirable to remove the metal between the round hole (which is illustrated) and the lower face of the reduced extension 39 of the bit blank, thereby forming a series of downwardly open slots or grooves. The advantage of the open slots is that they permit the molten metal to flow therethrough more rapidly and with less cooling effect, as compared with the closed holes 38.

What is claimed is:

1. Apparatus for casting an accurately centered diamond drill bit comprising a die having an annular recess perforated at the bottom for individually seating a plurality of diamonds and a central aperture, means cooperating with said die for receiving and retaining molten metal in association therewith during casting, means for producing suction through the perforations in said annular recess past said diamonds to retain the latter in position, a centering plug having a body portion adapted to extend through and support a bit blank in predetermined position above the die and terminating at one end in a central tip of reduced diameter, said central tip being adapted to fit into the central aperture in said die concentric with the annular recess therein, and means upon said centering plug for locating said bit blank a predetermined distance from said annular recess during the casting operation.

2. Apparatus for casting an accurately centered diamond drill bit comprising a die having an annular recess perforated at the bottom for individually seating a plurality of diamonds and a central aperture, means cooperating with said die for receiving and retaining molten metal in association therewith during casting, means for producing suction through the perforations in said annular recess past said diamonds to retain the latter in position, a centering plug having a body portion adapted to extend through and support a bit blank in predetermined position above the die and terminating at one end in a central tip of reduced diameter, said central tip being adapted to fit into the central aperture in said die concentric with the annular recess therein, a locating projection fixed upon the body portion of the centering plug and serving as a stop for locating the bit blank in predetermined position on said centering plug, and a removable holding member co-operating with the locating projection for retaining said bit blank in said predetermined position and thereby locating said blank a predetermined distance from said annular recess during the casting operation.

3. An apparatus for casting an accurately centered diamond drill bit comprising vacuum chamber means, a die supported on the vacuum chamber means and in communication therewith, said die having an annular recess perforated at the bottom for individually seating a plurality of diamonds and a central aperture concentric therewith, a flask ring supported on the die against lateral displacement relative thereto and adapted to receive and retain molten metal during the casting operation, a centering plug adapted to slidably support a hollow externally threaded bit blank in a predetermined position above the die, said plug having a pilot portion located in the central aperture of the die to position the blank concentric with the annular recess therein, said plug having a radially-extending flange serving as stop for locating the bit blank upon the plug, and an internally threaded removable cap passed down upon the plug and adapted to cooperate with the flange and the externally threaded bit blank to locate and retain the bit blank in a proper position relative to the annular recess of the die during the casting operation.
